United States Patent Office.

HENRY MEYER, OF RICHMOND, INDIANA.

Letters Patent No. 82,019, dated September 8, 1868.

IMPROVEMENT IN STOVE-PIPE DRUMS.

The Schedule referred to in these Letters Patent and making part of the same.

TO ALL WHOM IT MAY CONCERN:

Be it known that I, HENRY MEYER, of the city of Richmond, in the county of Wayne, and State of Indiana, have invented a new and useful Improvement for Heaters; and I do hereby declare that the following is a full and exact description.

My invention consists in a novel arrangement of flanges within the chamber of a stove-drum, which, in combination with a damper, divert the ascending currents of heated smoke and air, and cause the same to be delayed, thereby producing an increased radiation of the heat, and a consequent economy of fire.

In Figure I—

A gives a view of the outer cylinder and drum. The construction of the cylinder is the same as piping for stoves. The top cap of the drum is fastened to the cylinder by means of pinning.

B gives a view of the centre cylinder, extending through the drum A, and is constructed as the former. To this is fastened the stove-piping.

C gives a view of the bottom cap, having, on opposite sides, right-angular openings, which fasten the cap, when turned on the two pivots, stationed in the inside of the outer cylinder A. Thus the drum may be cleansed of the soot and ashes gathering in the bottom cap.

D gives a view of the damper, stationed in the upper part of the drum, regulated by means of a rod, passing through the cylinder A and B, and also passing through the damper, constructed of sheet iron, doubled, and is fastened to the same, as not to revolve around the regulating-rod.

On the top of said damper is constructed a right-angular flange, fastened to it by means of rivets, the perpendicular of the right-angle triangle bracing against the inner piping when closed. Said angular flange is to regulate the opening and closing of the damper.

In Figure II—

E and E' are two parabolical flanges, the one arm extending to the top, the other to the bottom of the drum. These parabolical flanges are of sheet iron, and are fastened obliquely to the centre pipe B by means of rivets. At the top and bottom of the parabolical flanges is a small perpendicular flange, joining the caps of the drum and the parabolical flanges, and is constructed like the former.

F and F' are small parabolical flanges, the upper arms joining the large parabolical flanges, in a distance of nearly one-third the length of the upper arms of said flanges, the lower arms extending downward the distance of about two-thirds the length from top of the drum, keeping equal distance with the lower arm of the larger flanges, and is constructed as the same.

G and G' are openings, conveying the smoke and heat into the drum. These openings are situated in the centre of the drum, the heat thus passing up the centre pipe, and the damper situated in the upper part of the drum, will be concentrated in said pipe, and be conveyed more regularly over all parts of the heater.

The heat entering these openings, is obliquely conveyed down the parabolical flues F E' and F' E, throwing a great part of its soot in the bottom cap, C, where, through a combustion, the soot will be consumed; thence it passes through the opening below the smaller flanges, F and F', where it rotates, and radiates up the parabolical flues, E F and E' F', till it reaches the openings H and H', situated above the damper; from thence it is permitted to escape.

What I claim as my invention, and desire to secure by Letters Patent, is—

The parabolical flues and damper, constructed and arranged in relation to each other and to the casing of the drum; substantially as set forth.

HENRY MEYER.
